UNITED STATES PATENT OFFICE.

GEORGE W. BOYD, OF RECTOR, ARKANSAS.

LAUNCHING APPARATUS FOR LIFE BOATS AND RAFTS.

1,162,218.

Specification of Letters Patent. Patented Nov. 30, 1915.

Application filed August 23, 1915. Serial No. 46,906.

To all whom it may concern:

Be it known that I, GEORGE W. BOYD, a citizen of the United States, residing at Rector, in the county of Clay and State of Arkansas, have invented certain new and useful Improvements in Launching Apparatus for Life Boats and Rafts, of which the following is a specification, reference being had to the accompanying drawings.

10 This invention relates to an improved launching apparatus for life boats and rafts and has for its primary object to provide a device of this character which will be automatically operated upon the sinking of 15 the vessel to which the same is applied, and the raft or boat released.

It is another important object of the invention to provide a launching apparatus for vessels embodying means whereby the 20 raft or boat may be elevated to a position above or below the deck of the vessel so that it will not interfere with the proper landing of the vessel at a wharf or the loading or unloading thereof.

25 The invention has for another and more specific object to provide a boat or raft, the body of which is mounted upon pontoons or air tanks, boxings arranged in pairs, and means mounted upon the hull of the vessel 30 for raising or lowering said boxings, means movable in the boxings and engaging the ends of the pontoons to support the raft or boat in position, and float actuated means for operating said supporting means where- 35 by the raft or boat is released.

It is a further general object of the invention to provide a device of the above character which is simple and durable in its construction, occupies but little room upon the 40 hull of the vessel, and is positive and reliable in its operation.

With the above and other objects in view, my invention consists in the novel features of construction, combination and arrangement of parts to be hereinafter more fully described, claimed and illustrated in the accompanying drawing, in which,

Figure 1 is a side elevation of a portion of a vessel showing my improved launching apparatus applied thereto; Fig. 2 is a horizontal section taken through one of the pontoons of the life raft. Fig. 3 is a section taken on the line 3-3 of Fig. 2; Fig. 4 is

a section taken on the line 4-4 of Fig. 1; and Fig. 5 is a section taken on the line 55 5-5 of Fig. 1.

Referring in detail to the drawings, 5 designates spaced vertically disposed channel bars which are bolted or otherwise rigidly secured to the side of the vessel's hull. 60 These channel bars constitute guides for the vertically movable racks 6. In suitable bearings, indicated at 7, fixed upon the channel bars 5, a horizontal shaft 8 is rotatably mounted. This shaft carries pinions 65 9 for coöperative engagement with the respective racks 6. Dogs 10 are also mounted in suitable brackets 11 fixed upon the channel bars 5, said dogs engaging the respective racks to retain the same in their ad- 70 justed positions. The shaft 8 may be operated from a motor or other suitable source of power.

To each of the rack bars 6, the spaced boxings 12 are suitably attached. In the 75 opposed walls of each of these boxings, a shaft 13 is rotatably mounted; and upon said shaft, an eccentric 14, located within the boxing, is fixed. Eccentric strap sections 15 are suitably mounted upon the periphery of the eccentric and connected at their extremities by the bolts 16. To one end of each shaft 13, an outwardly extending arm 17 is secured. The outer ends of the arms 17 of the respective pairs of shafts 85 13 are pivotally connected to a vertically disposed rod 18, upon the upper end of which a float 19 is adjustably secured by means of a set screw 20.

In the illustrated embodiment of my invention, I have shown a boat or raft embodying in its construction, the spaced pontoons or buoyant shells 21 upon which the body of the boat, indicated at 22, is mounted and suitably secured. Each of the pontoons 21 is provided with conical terminals 23 projecting beyond the opposite sides of the boat body. The pontoons are preferably connected and braced by means of bars or straps shown at 24. The body 22 of the 100 boat or raft may be provided with suitable automatically operating valves so that water entering the same may escape therefrom. Each of the pontoons 21 is provided adjacent one of its ends with a tapering, up- 105 wardly projecting, circular wall 25 sur-

rounding the manhole or opening, whereby access is afforded to the interior of the pontoon. A suitable cover or closure is provided for this opening. Within the pontoon, a cradle 26 is suitably suspended, upon which food and clothing and the valuables of the occupants of the boat may be placed.

Each of the boxings 12 is provided in its inner vertical wall with an opening 27 through which a supporting pin or rod 28, fixed at its inner end to the eccentric strap 15, extends. The outer ends of these pins 28 are pointed, as at 29, for engagement in the conical seats or recesses 30 formed in the tapering ends 23 of the pontoons.

In the operation of the apparatus, assuming that the device has been applied to the vessel as shown in Fig. 1, the bottom of the boat body 22 rests closely against the hull of the vessel. The boat or raft may be readily moved vertically with respect to the vessel by operating the shaft 8, whereby the racks 6 are moved in the guide channels 5. Thus, the boat can be so disposed that it will not obstruct the movements of the crew or the proper loading or unloading of the vessel. In the event that the vessel should sink, when the floats 19 strike the surface of the water, the rods 18 will be moved upwardly, thereby swinging the arms 17 inwardly and rotating the shafts 13. The eccentrics 14 are thus rotated to shift the straps 15 laterally and draw the pins or rods 28 inwardly and out of engagement with the ends of the pontoons 21. The life raft or boat is thus released so that it will float upon the surface of the water. In this manner, it will be seen that the detaching of the raft is automatic and the same cannot be carried down with the vessel, no matter how quickly the latter may sink. The invention, as a whole, is of exceedingly simple construction, may be readily applied to the ordinary vessel without requiring any alterations therein, and is reliable and positive in practical operation. By the provision of such an automatically operating launching apparatus, the lives of many of the passengers and the crew may be saved. It will, of course, be understood that the body of the raft or boat may be of any desired carrying capacity and a greater

or less number of the pontoons employed to sustain the same.

While I have shown and described the improved form and construction of the several elements employed, it is to be understood that my invention is susceptible of considerable modification therein and I, therefore, reserve the privilege of resorting to all such legitimate changes as may be fairly embodied within the spirit and scope of the invention as claimed.

Having thus fully described my invention, what I desire to claim and secure by Letters Patent is:—

1. In an apparatus of the character described, movable supporting elements to support a life boat upon the hull of a vessel, eccentrics coöperating with said elements to move the same, and float actuated means coöperating with the eccentrics to move the supporting elements and release the life boat.

2. In an apparatus of the character described, movable elements to support a life boat upon the hull of a vessel, rotatable shafts, eccentrics on said shafts, eccentric straps to which the movable elements are attached, arms fixed to said shafts, and a float actuated rod connecting the arms to operate the eccentrics and move the supporting elements whereby the life boat is released.

3. In an apparatus of the character described, spaced pairs of movable supporting elements for engagement with opposite sides of a life boat to support the same upon the hull of a vessel, eccentrics and eccentric straps to which the respective supporting elements are attached, a shaft for each eccentric and an arm fixed upon each of the shafts, rods connecting the arms of the respective pairs of eccentric shafts, and floats adjustable upon said rods whereby the arms are automatically operated to rotate the eccentrics and move the supporting elements whereby the life boat is released.

In testimony whereof I hereunto affix my signature in the presence of two witnesses.

GEORGE W. BOYD.
